(57) **CLAIM**

We claim the ornamental design for an information handling system, as shown and described.

DESCRIPTION

FIG. 1 is a front perspective view of the information handling system in a closed position comprising the present invention;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a front perspective view thereof in an open position;

FIG. 9 is a cross-sectional side view at the location indicated in FIG. 6; and,

FIG. 10 is a cross-sectional side view at the location indicated in FIG. 6.

Broken lines shown in the drawings illustrate portions of the information handling system and form no part of the claimed design.

1 Claim, 6 Drawing Sheets
